(57) **CLAIM**

I claim the ornamental design for a seatbelt shoulder pad with photo and ID pockets, as shown and described.

DESCRIPTION

FIG. 1 is a perspective view of a seatbelt shoulder pad with photo and ID pockets, showing my new design;

FIG. 2 is a front elevational view thereof;

FIG. 3 is a left-side elevational view thereof, the right-side elevational view being a mirror image thereof;

FIG. 4 is a rear elevational view thereof; and,

FIG. 5 is a top plan view thereof, the bottom plan view being a mirror image thereof.

The broken lines showing a photograph and emergency contact card in FIG. 1 depict environmental matter and form no part of the claimed design.
